UNITED STATES PATENT OFFICE

105,226

DESIGN FOR A MICROPHONE

Aston L. Moore, South Bend, Ind.

Application June 1, 1936, Serial No. 62,935

Term of patent 7 years

To all whom it may concern:

Be it known that I, Aston L. Moore, a citizen of the United States, residing at 1046 Lawndale Avenue, South Bend, Indiana, have invented a new, original, and ornamental Design for a Microphone, of which the following is a specification, reference being had to the accompanying drawing forming part thereof, in which

The figure is a perspective front view of a microphone showing my new design. The rear is substantially the same except that the dial and switch are omitted therefrom.

I claim:

The ornamental design for a microphone, substantially as shown and described.

ASTON L. MOORE.
